BOTTLE AND CAP THEREFOR

Filed Oct. 22, 1931

UNITED STATES PATENT OFFICE

CHARLES M. KRUGER, OF LITCHFIELD, ILLINOIS

BOTTLE AND CAP THEREFOR

Application filed October 22, 1931. Serial No. 570,282.

This invention relates to an improvement in bottles and caps therefor and consists in the novel construction hereinafter disclosed.

An object of this invention is to provide a bottle cap in combination with a specially formed bottle neck which is adapted to be readily applied to close the bottle and seal the neck together with means for preventing unauthorized contamination with the bottle 10 closure.

Another object of this invention is to provide in combination with the neck of a bottle a removable cap that may be adjusted on the neck of the bottle to effect a positive closure 15 thereof and which may be removed without damage to the cap.

More specifically an object of the invention is to provide a bottle with a specially formed neck in combination with a cap having a 20 cupped cap portion adapted to receive a sealing washer, the cap being provided with an elastic apron formed from spaced tongues in which a specially formed binding ring is mounted, together with a lever associated 25 with the binding ring to tightly clamp the cap in position and the lever being so formed and associated with the other parts as that it may be sealed against unauthorized movement by a destructible sealing band.

Additional advantages of the construction 30 will be readily apparent from the following detail description thereof taken in connection with the accompanying drawings, in which—

Fig. 1 is a top plan view of the bottle cap.

Fig. 2 is a side elevation of the bottle neck 35 with the cap applied thereto.

Fig. 3 is a view of the same parts viewed at substantially a right angle from Fig. 2.

Fig. 4 is a view of similar parts viewed at 40 an angle of 180° from Fig. 2.

Fig. 5 is a vertical section of the cap structure applied to the bottle taken substantially on a line 5—5 of Fig. 1.

Fig. 6 is a horizontal section taken substantially on the line 6—6 of Fig. 2.

Fig. 7 is a vertical section substantially on the line 7—7 of Fig. 1.

In the embodiment of the invention illustrated in the drawings the invention is shown 50 as environed in a bottle particularly adapt-

ed for use as a container for lubricating oil. It has become an established practice in merchandising lubricating oil to dispense it from containers filled at a common point and the seal of which is broken only at the time the oil is delivered to customers. The common practice has been to apply caps of usual construction that are forced from the neck of the bottle and the cap, therefore, destroyed when the contents of the bottle are dispensed. 60 The purpose of the destruction of the caps may be as readily accomplished by providing a destructible seal that is required to be broken before the removal of the cap but allowing the cap to be removed without distortion so that it may be re-used when the container is refilled. Furthermore it is an advantage to immediately replace the cap on the bottle after the contents have been dispensed so that in refilling the bottle it is unnecessary to wash them as the immediate replacement of the cap will prevent the content of the bottles from being contaminated by dust or dirt entering the neck of the bottle when the cap is entirely removed and not replaced. 70 It is also necessary on account of the required cleanliness in distribution of the lubricating oil that the cap tightly seal the bottle when in place. 75

An object of the invention is to provide a 80 bottle especially adapted for the purposes outlined although it will, of course, be understood that the use of the cap and bottle are not limited to these specific purposes.

In the embodiment of the invention illustrated in the drawings the bottle 1 is shown as including a specially formed neck 2 which is provided with an annular bead 3 around the bottle opening and a bead 4 around the neck of the bottle and at a space somewhat below the bead 3, thereby forming an intermediate circular section 5 of the bottle neck. The bottle cap is formed with a dished head 6 the depending walls of which are slotted to form a plurality of spaced arms 7 the lower 90 ends of which are upturned to form eyes 8. The depending portion of the head, including the slotted arms 7, provides an elastic apron for the bottle cap. The lower diameter of the bottle cap is sufficient to permit it to be 100

adjusted over the bottle mouth and the edge of the bead 3. The arms 7 are equally spaced except at the rear of the cap as shown in Fig. 4. One of the arms 7 is omitted at each side of the center line to form enlarged spaced openings 9, and at the front of the cap, as shown in Fig. 2, a plurality of the arms are omitted to provide an enlarged spaced opening 10. The head of the cap is adapted to receive interiorly thereof a washer 11 of any suitable sealing material such as prepared cork, fiber, or the like. Thus when the cap is fitted on the bottle neck the washer will be positioned over the upper edge of the bottle opening. A continuous binding ring, preferably in the form of an annular wire 12, is mounted in the eyes 8, the eyes being formed by turning the lower extremity of the arm 7 over the wire. The wire is provided with upwardly and inwardly deflected portions 13 in the segments of the wire that underlie the enlarged spaces 9 in the apron of the cap. These segments of the wire, when the cap is in position, extend into the shoulder formed by the face of the bottle neck and the bottom wall of the bead 3 and constitute spring bearing points against the bead 3. Mounted on that segment of the wire 12 that underlies the enlarged space 10 of the bottle cap apron is a lever 14, said lever including an outward convex section 15 and side flanges 16, the body of the lever thus formed merging into an outwardly deflected finger piece 17. The upper edge of the lever, when the lever is in adjusted position, is deflected outwardly slightly, as indicated at 18, Fig. 5, so that it engages under the shoulder formed between the face of the bottle neck and the lower face of the bead. The lever is mounted on the binding ring rearwardly of the ring by passing the ring through ears 19 formed in extension of the flanges 16. That segment of the ring that underlies the cutout section 10 is somewhat flattened as indicated at 20, Fig. 5. Thus when the cap is placed on the bottle neck and the lever swung downwardly to an adjusted position the outwardly extending edge 18 of the lever engages under the bead 3 after the lever has passed over center thereby forcing the portions 13 of the ring into close contact with the bead and engaging the bead at the front of the bottle cap along the upper edge of the lever. The inwardly deflected portion of the ring 20 bearing against the front face of the lever relieves the bearing of the ring on the ears 19. When the lever is thus operated it forces the entire cap downwardly and compresses the gasket 11 holding the parts in tightly sealed adjustment. The ring 10 is secured to the arms 7 that lie between the spaces 9 at the rear of the cap but the ring is free to move in the eyes beyond the spaces 9. Thus as the lever is depressed the flat portion 20 of the ring is forced outwardly exerting a circumferential pull on the seg-

ment of the ring lying in the long direction between the portions 13 thereof. This permits the upper edge of the lever to find its seat against the bead 3 and the portion 20 of the ring then presses against the front face of the lever holding the upper edge of the lever firmly in place against the bead 3.

After the cap has been adjusted the lever is held against unauthorized manipulation by a destructible band seal 21 fastened about the neck of the bottle and across the face of the lever. It should be noted that the lever 14 is provided with a flat section intermediate the beads 3 and 4 and that the portion of the lever that extends below the bead 4 is deflected so that it rests flat against the face of the bottle neck and the face of the bead 4. That portion of the lever lying between the beads 3 and 4, when the lever is in assembled position, is encompassed by the destructible seal and since it is not possible to remove the cap without raising the lever to disengage the upper edge thereof from the bead, the cap cannot be removed without breaking the seal.

I am aware that the invention may be modified, in numerous particulars, without departing from the spirit and scope of the invention. I do not limit myself, therefore, to the specific constructions shown and described, but what I claim and desire to secure by Letters Patent is:

1. The combination with a bottle having a circular bead at the bottle opening forming a shoulder, of a cap comprising a head portion adapted to fit across the bottle opening, an elastic apron connected with the head portion, a binding ring supported by the apron, said binding ring having upwardly and inwardly projecting segments at one side adapted to fit against the shoulder formed by the bead, and a lever connected with said binding ring and positioned on the opposite side from said segments and adapted to engage the bead and to expand said ring and seat the cap.

2. The combination with a bottle having a circular bead at the bottle opening forming a shoulder, of a cap comprising a head portion adapted to fit across the bottle opening, an elastic apron connected with the head portion, a binding ring supported by the apron, said binding ring having upwardly and inwardly projecting segments at one side adapted to fit against the shoulder formed by the head, a lever connected with said binding ring and positioned on the opposite side from said segments and adapted to engage the bead and to expand said ring and seat the cap, and a destructible band adapted to encompass the lever and be supported by the neck of the bottle for preventing the lever from being released without breaking the band.

3. The combination with a bottle having a neck having spaced beads one surrounding

the bottle opening and the other circumferentially encircling the neck, a cap having a head portion and a flexible apron, a ring connected with the lower portion of the apron, a lever supported by the ring having an upper edge conforming to and adapted to seat against the upper one of said beads and arranged to clamp the cap in position on the bottle when the lever is in a lowered position, and a destructible band encircling the lever and positioned in the space between said beads.

4. A bottle cap comprising a dished head portion having depending arms forming a flexible apron, a ring supported by said arms, said ring having inwardly and upwardly deflected portions adapted to engage a shoulder on the bottle neck, and a lever carried by said ring the upper edge of said lever being arranged to engage a shoulder formed on the bottle neck to force the cap downwardly and tighten the ring and the other portion of said lever being adapted to depend downwardly adjacent to a face of the bottle neck.

5. A bottle cap comprising a head portion and a flexible apron, a binding ring having an inwardly deflected portion supported at the lower edge of said apron, and a lever connected to said ring having an upper edge portion to engage a shoulder formed on the bottle neck and positioned to bear against the inwardly deflected portion of the said ring.

6. A bottle cap comprising a head portion and a flexible apron, a binding ring having an inwardly deflected portion supported at the lower edge of said apron and being secured thereto at one point and movable in respect thereof at each side of the point of securing, and a lever connected to said ring having an upper edge portion to engage a shoulder formed on the bottle neck and positioned to bear against the inwardly deflected portion of the said ring.

7. The combination with a bottle having a circular bead at the bottle opening forming a shoulder, of a cap comprising a head portion adapted to fit across the bottle opening, a gasket interposed between the under face of the head portion and the upper edge of the bottle neck, an elastic apron connected with said head portion, a binding ring supported by the apron, said binding ring having upwardly and inwardly projecting segments at one side adapted to fit against the shoulder formed by the bead, and a lever on the opposite side adapted to engage the bead and seat the cap.

CHARLES M. KRUGER.
